Primary Examiner — Susan Moon Lee(74) *Attorney, Agent, or Firm* — Ash Tankha; Lipton, Weinberger & Husick(57) **CLAIM**

The ornamental design for a grooming apparatus, as shown and described.

DESCRIPTION

FIG. 1 is a front orthographic view of a grooming apparatus;
 FIG. 2 is a side sectional view thereof;
 FIG. 3 is a rear orthographic view thereof;
 FIG. 4 is a bottom orthographic view thereof;
 FIG. 5 is a front isometric view thereof; and,
 FIG. 6 is a rear isometric view thereof.
